HANDLE ATTACHMENT LOOP FOR LUGGAGE

Abraham Levine, Mendham, N.J., assignor to Presto
Lock Co., Garfield, N.J., a limited partnership

Filed June 3, 1958, Ser. No. 51,179

Term of patent 14 years

(Cl. D87—2)

Fig. 1

Fig. 3

Fig. 1 is a top plan view of the handle attachment loop for luggage embodying my design;

Fig. 2 is a side elevational view of the same; and

Fig. 3 is an end elevational view of the same, viewed from the right in Fig. 2.

I claim:

The ornamental design for a handle attachment loop for luggage, as shown.
